ROBERT HAMILTON AND ELMER J. REIMEL, OF BIRMINGHAM, ALABAMA.

DRAG-CAR.

1,345,439.

Specification of Letters Patent.

Patented July 6, 1920.

Application filed May 29, 1919. Serial No. 300,548.

To all whom it may concern:

Be it known that we, ROBERT HAMILTON and ELMER J. REIMEL, citizens of the United States, residing in Birmingham, county of Jefferson, and State of Alabama, have invented certain new and useful Improvements in Drag-Cars, of which the following is a specification.

Our invention relates to improved means for moving empty work cars from the entry of a mine into the work rooms thereof and for subsequently hauling the loaded cars out of the workrooms and along the entry of the mine. Heretofore these work cars have been drawn by a mule and in thin veins of low coal it was necessary to shoot down a considerable portion of the roof in order to permit the mule to enter. This practice was objectionable due to the time consumed and the expense involved. In some instances where low coal is encountered manual labor is utilized for moving the work cars which is a costly and inefficient way of doing the work. In thin seams of coal when the work cars have to be pushed in and out of the room by mules or by hand; if the length of the room is greater than 250 feet, the expense involved in operating the work cars runs the cost of the mining to a higher figure than would be the case if new entries were driven and short rooms turned off of them.

Our invention reduces this labor cost and by its utilization, rooms of great length can be used thereby reducing the number of entries required which results in great saving in the cost of construction and in the operating expenses of a mine.

One of the objects of the invention is to eliminate the man power required in handling cars. Another object is to increase the daily output of coal delivered by each miner. A further object is to provide a car capable of moving the work cars within the working room of the mine and hauling them along the mine entry. Another object is to provide a drag car having reels and driving mechanism mounted thereon in such a way as to enable the center of gravity of the car to be kept at a low point to prevent the over turning of the drag car when pulling a heavy load. Another object is to combine the various elements herein described so as to effectively perform their various functions. Other objects will be apparent from

the following description when read in connection with the accompanying drawings.

Figure 1 is a side elevation of a double reel drag car constructed in accordance with our invention;

Fig. 2 is a plan view thereof;

Fig. 3 is a detail view illustrating a silent chain drive for transmitting power from a common motor to the two drag wheels shown in the above figures;

Fig. 4 is a diagrammatic horizontal section showing the mine entry and working room and illustrating the operation of the double reel drag car;

Fig. 5 is a side elevation of a single reel car embodying our invention parts being shown in section on the line 5—5 of Fig. 6;

Fig. 6 is a plan view thereof;

Fig. 7 is a detail section on the line 7—7 of Fig. 6;

Fig. 8 is a detail of a coupling pin employed for establishing a driving connection between the drag reel and its driving worm gear;

Fig. 9 is a horizontal section showing diagrammatically the single reel drag car in operation.

Our improved drag car comprises a frame A supported on wheels B and C, the wheels B being loosely mounted on the axles B', and the wheels C being fixedly secured to their axles C'. The truck frame A supports a motor D on one end of the armature shaft of which is secured a sprocket H and to the other end of which is secured a driving pinion D'. Drag reels E and F are mounted for free rotation on vertical spindles J and J' each of which is driven by a worm gear similar to that illustrated at J² in Fig. 7. The spindles J and J' are supported at their upper ends in brackets J³ and at their lower ends in bosses J⁴ formed in the gear casing J⁵.

Bearings L and N are provided to reduce the friction due to the weight of the reels and the thrust of the worm gears. The gear case J⁵ is adapted to contain oil or grease for lubrication of the parts and a cover plate serves to prevent splashing out of the lubricant and to exclude foreign matter from the interior of said casing.

The worm gears J² are each driven by a worm L secured to a shaft L' on the outer end of which is secured a sprocket L². A chain G passes over the sprocket H and

around the sprockets L^2-L^2 for driving the worms $L-L$ and consequently the reels E and F . An idler sprocket K is provided to secure a good arc of contact between the chain and the sprockets and to adjust the tension of this chain. The reels E and F are each provided with a plurality of apertures Q and the worm gear J^2 is provided with an aperture R . When the apertures Q and R are in line a coupling pin P may be inserted to effect a driving engagement between either of the drag reels and its corresponding worm gear J^2 .

As thus constructed it will be seen that the motor D is capable of independently driving either of the drag reels E and F according to which one the coupling pin P is inserted in. This arrangement permits an operator to use one of the drag reels for winding up cable and the other for paying off cable in a manner to be described hereinafter.

For controlling the propelling of the truck a countershaft b mounted in suitable bearings secured to the truck is provided. On one end of this shaft a sprocket b' is fixedly secured and on the other end a gear a provided with a clutch face a' and meshing with the gear D' is loosely mounted. A clutch member d is splined to the countershaft b and is adapted to be moved by a control lever c into engagement with the clutch member a' secured to the gear a . A sprocket chain c connects the sprocket b' with a sprocket C^2 secured to the shaft C' whereby power is transmitted from the counter-shaft b to the driving axle C' .

A controller f carried by the frame A serves to govern the starting and stopping of the motor D as well as to control the speed thereof. The current for the motor D is supplied in any suitable manner, for example, by means of an overhead trolley wire h indicated in Fig. 2, and a trolley pole h' supported on an upright h^2 secured to cross-beams A' serves to convey the current from the feed wire in a well known manner, the current returning by way of the wheels through the tracks.

In operation when it is desired to remove coal or other ore from one of the workrooms W of a mine the drag car is driven along the tracks T of the mine entry V in some instances towing with it a number of work cars which are not provided with any self-propelling means. A branch track T' is connected by means of a suitable spur with the workroom and provides means for guiding the work cars within the workroom.

Fig. 4 illustrates an arrangement in which the work cars can be moved into and out of the workrooms by means of the drag reels E and F carried by the drag car, and Fig. 9 illustrates the operation of the single reel

drag car shown in Figs. 5 and 6 which is adapted for pulling a loaded car out of the workroom.

Referring first to Fig. 4 the drag car pulls an empty work car up to position indicated at u where the trip rider or operator secures it in any suitable manner, for example by means of a short length of cable u' to a cable w which passes around a guide sheave x secured in place on a stake or other suitable means within the workroom and near the working face. One free end z of this cable w is fastened to the free end of the cable wound on the reel F and the other end y of the cable w is fastened to the end of the cable carried by the reel E .

In order to draw the work car u into the workroom and up to the face of the work, the operator removes the coupling pin P from the reel F and inserts a coupling pin in the reel E to effect a driving engagement between said reel and its corresponding worm gear J^2 . The motor is then started to drive the worm gearing which clearly will rotate the reel E and thereby wind up the cable w and cause the movement of the cable in the direction indicated by the arrow z' and cause the work car U to be hauled up to the position indicated at v . After the empty car has been moved up to the position shown at v the operator on the drag car will stop the motor and remove the coupling pin from the reel E and insert it in the reel F and the workman in the room will disconnect the empty car from the cable w and will connect a loaded car s therewith by means, for example, of a short cable s' and will then signal the operator on the drag car who will again start the motor which will cause the reel E to withdraw the loaded work car s . This will bring the free ends y and z of the cable w to the position shown in the drawing where they may be disconnected from the cables carried by the reels E and F and they will therefore be in position for subsequent operation similar to that described and the loaded car may be connected to one of the cables on either the reels E and F and be towed along a mine entry V to a dumping station or any other desired location.

When a single reel drag car is used as illustrated in Fig. 9 the drag car is driven up to the throat of the working room and the trip rider removes the pin P from the reel E and takes hold of the free end of the cable wound thereon and connects it to the empty car m which is then in the position shown in dotted lines, and shoves the car along the branch track T' to the position shown at u . After the car is loaded the coupling pin P is put in place and on signal from the workman within the room the operator on the drag car starts the motor to

cause the rotation of the drag reel thereby hauling the loaded car out into the mine entry.

The operator on the drag car can then 5 throw the clutch *d* into engagement with the clutch member *a'* carried by the gear *a* and the drag car will then be driven along with the loaded work car in tow.

From the above it will be seen that our 10 invention provides an improved means for handling the work cars in a mine whereby greater speed is attained and considerable manual labor with its attendant expense is eliminated. By using a worm gear drive 15 for the drag reels we are enabled to construct a car requiring very little head room and also one having a low center of gravity and therefore less liable to tip over when hauling a heavily laden work car. The 20 worm drive also affords a safety feature of no little importance because in the event of the motor failing for any unforeseen reason while a car is being drawn up an inclined track, the same would not be able to run 25 wild, the worm gear not being able to drive the worm and thereby preventing accident and loss of property.

Though we have described with great particularity the details and construction of the 30 embodiments of the invention herein shown, yet it is not to be understood therefrom that we are limited thereto as changes in construction and substitution of equivalents may be made by those skilled in the art 35 without departure from the invention as defined in the appended claims.

What we claim is:

1. In a mine a longitudinal entry, a lateral 40 working room communicating therewith, a drag car movable along said entry, work cars adapted to be loaded in said mining room, a guide sheave and cable in said room adapted to be connected with said work cars, and means carried by said drag car and co-acting 45 with said guide sheave and cable to move

the work cars into and out of said mining room.

2. In a mine a longitudinal entry, a lateral working room communicating therewith, a drag car movable along said entry, work 50 cars adapted to be loaded in said mining room, a guide sheave and cable in said room adapted to be connected with said work cars, a motor for propelling said drag car, drag reels carried by said car and arranged 55 to be driven by said motor, means for establishing and disengaging the driving connection between said motor and said drag reels, whereby said reels coact with said sheave and cable to alternately move said 60 work cars into and out of said mine room.

3. A drag car comprising a truck having a drag reel mounted thereon, worm gearing for driving said drag reel, a casing for enclosing said worm gearing and holding a 65 lubricant therefor, a motor for driving said worm gearing and propelling the truck and a removable pin for establishing a driving connection between said drag reel and said worm gearing.

4. A drag car comprising a truck having a drag reel freely mounted on a shaft, a worm gear secured to said shaft, a worm for driving said gear, a motor operatively connected with said worm and means for engaging and disengaging the drag reel and the 75 worm gear.

5. A drag car comprising a truck having a drag reel freely mounted on a vertical shaft, a worm gear secured to said shaft, a 80 worm for driving said gear, a motor whose shaft extends crosswise of said truck operatively connected with said worm and means for engaging and disengaging the drag reel and the worm gear.

In witness whereof, we have hereunto signed our names.

ROBERT HAMILTON.
ELMER J. REIMEL.
